SURGICAL INSTRUMENT

Samuel J. Blumenthal, Brooklyn, N. Y.

Application May 20, 1938, Serial No. 208,983

8 Claims. (Cl. 128—309)

This invention relates to surgical instruments designed primarily for use in the removal of tonsils or in performing what is commonly termed tonsillectomy by instruments termed tonsillotomes; and the object of the invention is to provide an instrument of the character described having an improved blade construction with improved means for actuating the several blades employed so as to materially simplify the performance of the operation so as to render the results more effective and fool-proof while at the same time materially simplifying the operations of the surgeon in performing the operation; a further object being to provide an instrument of the character described wherein upper and lower blades or jaw members are employed, each having an independent movement toward and from the crosshead at the free end of the instrument, and within and between which a supplemental cutter blade is movably disposed and movably independent of the first named blades or jaws but frictionally engaging the upper jaw whereby the latter may be released from the edges of the pillars around the tonsil so as to permit the removal of the instrument with the tonsil remaining supported in connection with the instrument by the lower blade or jaw; a still further object being to provide an instrument of the character described wherein the separate blades are detachable with respect to the shank or main body portion of the instrument and wherein all of the blades including the body of the instrument are plain and unobstructed especially at the outer portions thereof, thus simplifying the cleansing and sterilization of the instrument, eliminating all unnecessary crevices and recesses which would otherwise render the instrument objectionable and at the same time facilitating the free and simplified use of the instrument in performing an operation; a further object being to provide means for quickly attaching and detaching the various parts of the instrument including a lever action for quickly moving the blade into its operative and inoperative positions, and with these and other objects which will hereinafter appear, the invention consists in a device of the class and for the purpose specified which is constructed as hereinafter more fully described and claimed.

The invention is fully disclosed in the following specification, of which the accompanying drawing forms a part, in which the separate parts of my improvement are designated by suitable reference characters in each of the views, and in which:

Fig. 1 is a side view of an instrument made according to my invention indicating two positions of certain parts thereof.

Fig. 2 is a longitudinal sectional view through the device as seen in Fig. 1.

Fig. 3 is a detail view of the cutter blade unit detached.

Fig. 4 is a section on the line 4—4 of Fig. 2.

Fig. 5 is a view similar to Fig. 2 showing only one end portion of the instrument and illustrating the first position of the blades in performing an operation.

Fig. 6 is a view similar to Fig. 5 showing the next position of the blades.

Fig. 7 is a view similar to Figs. 5 and 6 showing the next successive positions of the blades.

Fig. 8 is a view similar to Figs. 5, 6 and 7 showing a further position of the blades, and

Fig. 9 is a plan and sectional view of one end portion of the instrument with parts of the construction broken away.

Instruments of the type and kind under consideration, were originally referred to as guillotines, and are utilized primarily in performing tonsillectomy and are not employed when the particular nature of the tonsil is such as to require operation by dissection. It is the purpose of my invention to provide an instrument of this type and kind, commonly referred to as a tonsillotome which will simplify the performance of operations of the character described and insure a more perfect performance of the operation with the least amount of throat soreness after the performance of the operation and without danger of destruction to the pillars of the throat at the tonsil, leaving the maximum amount of musculature after the removal of the tonsil.

In the accompanying drawing, I have shown at 10 the shank or body portion of the instrument which is in the form of an elongated bar preferably rounded on its lower surface and having a flat top surface 11. The outer end of the bar 10 is flattened and widened as seen at 12 to form a support for an enlarged or wider head 13, the upper surface of which is continuous with the surface 11 as will appear in Fig. 2 of the drawing. This surface or wall is provided with an elliptical aperture 14 in the outer end portion thereof within the curved or semicircular outer crosshead 15. The crosshead 15 is of 30 channelled cross sectional form and opens into channelled sides 16 on the head 14 to form upwardly and inwardly turned flanges. The channelled sides 16 terminate at the inner end of the head as seen at 17 and open through the head at 55

this point to permit movement of blades later described back and forth through the head.

The outer side portions of the channelled crosshead 15 include a facing 18 preferably of soft metal so as not to injure the edge of the cutter blade, later described, when moved into engagement with the crosshead in the operation of severing the tonsil as later described.

At the rear portion of the body or frame 10 is a downwardly extending handle 19 preferably arranged at a slight inclination and part only of which is shown in the drawing. The handle is of sufficient length to provide a suitable hand grip for supporting the instrument in one hand. The upper end of the handle 19 includes side plates 20 which are welded or otherwise secured to the frame bar 10 or may be formed as an integral part thereof if the frame is made from a casting. The plates 20 extend above the surface 11 to form between the side plates a channel within which a top blade 21, bottom blade 22 and intermediate cutter blade 23 are movably disposed. The upper ends of the plates 20 are provided with bayonet apertures 24 opening through the upper edges thereof. One of the side plates 20 is provided with projecting ears 25 within and between which a lock bar 26 is pivotally mounted as seen at 27, note Fig. 4. The bar is adapted to be arranged in part of the bayonet apertures 24 as seen in Fig 1 of the drawing and provides means for retaining the blades in position and for supporting the T-shaped crosshead 28 of a rod 29 against displacement from the frame or the side plates 20 thereof. The outer surface of the lock bar 26 is milled as seen at 26a to facilitate movement thereof into an open position, the bar being frictionally supported in its operative position.

The rod 29 is adjustably coupled with the internally threaded portion of a link 30, the rod 29 being in threaded engagement therewith so as to adjust the length of the crosshead of the link with respect to the pivot 31 thereof with an operating lever 32. The lever 32 is pivoted as seen at 33 to an enlarged portion 34 arranged at the inner end of the cutter blade 23, and the parts 29, 30, 32 are normally assembled with the blade 23 or the enlargement 34 thereof to form a unit attachable and detachable as such with respect to the instrument.

The forward end 35 of the blade 23 is sharpened and curved to conform with the curvature of the crosshead 15, the sharpened or beveled edge extending well onto the sides of the blade as indicated at 35a in Fig. 3 of the drawing so as to insure the performance of a cutting operation throughout the full length of the crosshead 15 or the side portions thereof. By beveling the edge of the blade downwardly, the upper surface of the blade 23 will slide freely over the lower surface of the blade 21, and also keep the severing operation as near the pillars of the throat as possible, thus leaving the least amount of tissue. The end portion 35b of the blade 23 is of a width to fit freely within the side channels 16 of the head 13, whereas the remainder of the blade proper is substantially of the same width as the shank 10. The enlargement 34 is narrow and arranged centrally of the inner end of the blade and includes an elongated key portion 36 adapted to operate in an elongated aperture 37 in the corresponding end of the blade 21, the aperture 37 opening through said end of the blade.

Inwardly of the inner end of the blade 21, the

side edges thereof are extended and twisted to form laterally extending wings or finger piece portions 38 by means of which the blade 21 may be moved forwardly by either hand of the operator or from either side of the instrument. The forward end 29 of the blade 21 is enlarged to fit snugly within the channel 16, whereas the remainder of the shank of said blade corresponds in width to the blade 23 and the shank of the tool.

The free edge of the blade 21 or the head 39 thereof is curved as seen at 40 to conform with the contour of the crosshead 15. While this end may be blunt or the width carried to the crosshead, in certain types of tools, it is preferred to bevel the upper surface of the head 37 as seen at 41 so as to produce a thinner, but not sharp edge 40. This construction will facilitate more readily the inversion of the tonsil and at the same time will reduce the thickness of the head 13 as a whole and especially at the crosshead portion 15 thereof.

The blade 21 is held in position by the crosshead 28 of the rod 29 as well as by the lock bar 26, and this also holds the other blades 22 and 23 in position, the blade 22 otherwise forms an independent unit freely detachable as is the blade 23 and the blade 22.

The blade 22 has at its outer end an enlarged head 42 generally similar to the enlarged heads 30 of the blades 21 and 23 so as to fit within the channels 16 and be guided thereby. This blade terminates at its free end with a curved edge 43, also conforming to the crosshead 15, as will be apparent. The shank of the blade 22 is of similar width to the other blades and is provided at its inner end with an enlarged body 44 having a depending fork-shaped portion 45 and a forwardly hook-shaped top portion 46, the rear end of which is provided with laterally extending finger pieces or wings 47 facilitating the movement of the blade 22 at either side of the instrument.

The lower forked end 45 of the block 42 extends over a rearwardly extending threaded rod 48 constituting part of the bar or frame of the instrument. The threaded rod has a head 49 at the outer end thereof to limit the outward movement of a winged nut 50 having large laterally extending wings 51 to facilitate spinning of the nut 50. The threads are preferably of a quick type to facilitate quick forward advancement of the nut in the spinning thereof to engage the block 44 in holding the blade 22 firmly in position with the edge 43 thereof engaging the tonsil between it and the crosshead 15.

In assembling the instrument, the blade 22 is first arranged upon the upper surface of the frame with the yoke 45 spanning the screw 48 and with the block 44 adjacent the winged nut when in its position adjacent the head 49. After this the other blades 23 and 21 may be arranged separately upon the blade 22 or the blades 21 and 23 may be assembled with the forked end of the blade 21 engaging the key 36, and as assembled placed upon the blade 22, after which the free ends of the respective blades will be moved forwardly and guided into the channels 16. The crosshead 24 is then moved downwardly and then rearwardly in the bayonet apertures 24. It will be understood, however, that the lock bar 26 is in the open position in the aforesaid operations, after which the lock bar 26 is moved into closed position and the respective blades moved rearwardly to fully expose the aperture 14 in the head 13 of the instrument.

In this position of the parts, the lever 32 will be in a forwardly inclined position substantially similar to that shown in full lines in Figs. 1 and 2, whereas the wings 38 of the blade 21 will be arranged substantially at the forward end of the screw 48 or where the screw joins the shank proper of the instrument.

The instrument is now ready for use, and the tonsil to be severed is pushed through the opening 14 of the head 13, and in this operation, the blade 21 is advanced in the direction of the crosshead 15 by the thumb of the hand grasping the handle 19 while one finger of the other hand is arranged upon the upper surface of the head 39 of the blade 21 adjacent the edge 40 to insure a complete and proper inversion of the tonsil. This operation is continued until the entire tonsil has been inverted and protrudes below the lower surface of the instrument and the tissue adjacent the pillars is supported between the edge 40 and the crosshead 15 so as to firmly but not severely support the tissue in this position. This operation can be controlled by the pressure of the thumb upon one of the wings 38. The result of this operation is indicated in Fig. 5 of the drawing.

The next step consists in moving the bottom blade 22 forwardly by a finger of the free hand and then spinning the winged nut 50 and tightening it sufficiently to firmly and securely hold the tonsil in close proximity to the engagement of the blade 21 with the tissue as above stated, as seen in Fig. 6. After this the lever 32 is grasped and moved backwardly into the dotted line position shown in Fig. 1, which operation will move the cutter blade 23 forwardly and sever the tonsil between the two blades 21 and 22 as seen in Fig. 7. After this the thumb is released from the wing 38 of the blade 21, and the lever 32 is then moved forwardly with a quick stroke, in which operation the retraction of the cutter blade 23 by reason of its frictional engagement with the blade 21 will cause the blade 21 to be drawn rearwardly to disengage the throat tissue and thus leave the tonsil supported in the instrument by the blade 22 as illustrated in Fig. 8 of the drawing, and facilitate the removement of the tonsil from the mouth by the instrument, after which the winged nut 50 is released and all of the blades moved rearwardly by a single pressure applied upon either one of the wings 38 which will free the tonsil from the instrument. The instrument is now ready for the repeating of the above operation for the removal of the second tonsil.

In the above described rearward frictional movement of the blade 21, it will appear that sufficient clearance is provided between the rear edge of the blade and the block 44, note Fig. 1, to permit this free movement, while at the same time the block checks the rearward movement of the blade 21 so as to provide a sufficient opening to free the tissue. In the event that sufficient forward movement of the blade has not been accomplished to completely sever the tonsil, it will be understood that the blade 21 may be again moved forwardly and the blade 23 advanced forwardly with greater pressure to fully complete this operation. However, by reason of the structure employed, the complete severing of the tissue is substantially assured. By providing the soft metal lining 18 in the crosshead, an imbedding of the cutting edge 35 of the blade into this metal is provided, which will produce positive severance of the tonsil, as will be apparent.

By providing the adjustable rod 39, it will be understood that the movement of the lever 32 in controlling the operation of the blade 23 may be regulated.

It will be understood that any suitable means may be provided for quickly moving and supporting the blade 22 in operative position and for holding the same in such position until such time as the tonsil is ejected from the instrument after removal from the throat.

It will of course be understood that the illustrations in the drawing of the tonsil are purely diagrammatic and are not to be considered characteristic of any particular tonsil or throat structure adjacent the tonsil.

Having fully described my invention, what I claim as new and desire to secure by Letters Patent, is:

1. An instrument of the class described comprising an elongated body portion enlarged at the outer end thereof, the enlarged end having a substantially elliptical aperture forming an arc-shaped crosshead at the outer edge of said end of the instrument which is of channelled cross sectional form and continuous with channelled sides of said enlarged end, three elongated blades arranged upon and movable longitudinally of said body and having enlarged outer ends operating in and guided in the enlarged channel portion of said body, a handle member at the other end portion of said body, each of said blades having means at said end portion of the instrument for independently moving the same longitudinally of the body toward and from the curved crosshead, the outer ends of said blades being curved to conform with the contour of said crosshead, one of said blades being disposed intermediate the other two blades and having a sharpened edge at its free end to form the knife of the instrument.

2. An instrument of the class described comprising an elongated body portion enlarged at the outer end thereof, the enlarged end having a substantially elliptical aperture forming an arc-shaped crosshead at the outer edge of said end of the instrument which is of channelled cross sectional form and continuous with channelled sides of said enlarged end, three elongated blades arranged upon and movable longitudinally of said body and having enlarged outer ends operating in and guided in the enlarged channel portion of said body, a handle member at the other end portion of said body, each of said blades having means at said end portion of the instrument for moving the same longitudinally of the body toward and from the curved crosshead, the outer ends of said blades being curved to conform with the contour of said crosshead, one of said blades being disposed intermediate the other two blades and having a sharpened edge at its free end to form the knife of the instrument, said knife blade being movable relatively to the other blades when the free ends of said other blades are disposed in close proximity to said crosshead, and one of said blades being frictionally moved by the knife blade when the latter is moved in the direction of the handle end of the instrument.

3. An instrument of the class described comprising an elongated body portion enlarged at the outer end thereof, the enlarged end having an aperture, an arc-shaped and channelled crosshead at the outer end of the instrument, three elongated blades arranged upon and movable longitudinally of said body and having enlarged and rounded outer ends, a handle member at the

- other end portion of said body, one of said blades forming the knife of the instrument and being movable between and relatively to the other blades when the free ends of said other blades are disposed in close proximity to said crosshead, means for operating the knife blade comprising a lever pivotally coupled with the inner end of the knife blade, and an adjustable link for pivotally coupling the lever in connection with the instrument body.
4. An instrument of the class described comprising an elongated body portion enlarged at the outer end thereof, the enlarged end having an aperture, an arc-shaped and channelled cross-head at the outer end of the instrument, three elongated blades arranged upon and movable longitudinally of said body and having enlarged and rounded outer ends, a handle member at the other end portion of said body, one of said blades forming the knife of the instrument and being movable between and relatively to the other blades when the free ends of said other blades are disposed in close proximity to said crosshead, means for operating the knife blade comprising a lever pivotally coupled with the inner end of the knife blade, an adjustable link for pivotally coupling the lever in connection with the instrument body, and means involving a lock bar for supporting the link against displacement from said body.
5. An instrument of the class described comprising an elongated body portion enlarged at the outer end thereof, the enlarged end having an aperture, an arc-shaped and channelled cross-head at the outer end of the instrument, three elongated blades arranged upon and independently movable longitudinally of said body and having enlarged and rounded outer ends, a handle member at the other end portion of said body, one of said blades forming the knife of the instrument and being movable between and relatively to the other blades when the free ends of said other blades are disposed in close proximity to said crosshead, means for operating the knife blade in both directions, and manually operated means for supporting one of the second named blades in its forwardly extended position.
6. An instrument of the class described comprising an elongated body portion enlarged at the outer end thereof, the enlarged end having an aperture, an arc-shaped and channelled cross-head at the outer end of the instrument, three elongated blades arranged upon and movable longitudinally of said body and having enlarged and rounded outer ends, a handle member at the other end portion of said body, one of said blades forming the knife of the instrument and being movable between and relatively to the other blades when the free ends of said other blades are disposed in close proximity to said crosshead, means for operating the knife blade comprising a lever pivotally coupled with the inner end of the knife blade, and an adjustable link for pivotally coupling the lever in connection with the instrument body, and means involving a lock bar for supporting the link against displacement from said body.
7. In a tonsil removal instrument of the class described, the outer end of which is provided with a large opening through which a tonsil to be removed is adapted to be passed, the opening being bounded on its outer side by a crosshead, a blade movable toward and from said crosshead to engage the tissue adjacent the pillars when a tonsil has been inverted through said opening, another blade independently movable toward and from the crosshead for firmly engaging the tonsil in juxtaposition to, but in slight spaced relation to the engagement of the first mentioned blade with the tissue, means for positively controlling the engagement of the second named blade, and means disposed between the first named blades and independently movable relatively thereto for severing the tonsil intermediate said blades.
8. In a tonsil removal instrument of the class described, the outer end of which is provided with a large opening through which a tonsil to be removed is adapted to be passed, the opening being bounded on its outer side by a crosshead of channelled cross sectional form, a blade movable toward and from said crosshead to engage the tissue adjacent the pillars when a tonsil has been inverted through said opening, another blade movable toward and from the crosshead for firmly engaging the tonsil in juxtaposition to, but in slight spaced relation to, the engagement of the first mentioned blade with the tissue, means for positively controlling the engagement of the second named blade, means disposed between the first named blades and movable relatively thereto for severing the tonsil intermediate said blades, and said first named blade being in frictional engagement with said last named means whereby the movement of the last named means away from said crosshead will automatically move said blade into inoperative engagement with the tissue to free the instrument from the throat leaving the tonsil suspended in the instrument between the second mentioned blade and said crosshead.

SAMUEL J. BLUMENTHAL.
